UNITED STATES PATENT OFFICE.

FERDINAND KREUTER, OF NEW YORK, N. Y.

DESIGN FOR AN EYEGLASS-GUARD.

SPECIFICATION forming part of Design No. 32,056, dated January 2, 1900.

Application filed September 15, 1899. Serial No. 730,639. Term of patent 14 years.

To all whom it may concern:

Be it known that I, FERDINAND KREUTER, a citizen of the United States, and a resident of New York, in the county of New York and State of New York, have invented and produced a certain new and useful Design for Eyeglass-Guards, of which the following is a specification.

In the accompanying drawings, to which reference is made and which form a part of this specification, Figure 1 is a front elevation of a nose-guard for eyeglasses, showing my new design. Fig. 2 is a rear elevation of the same, and Fig. 3 is an edge view of the same.

The leading feature of my design consists of an eyeglass-guard of the configuration shown in the drawings, the same consisting

of two parallelograms in a plane with each other and united edge to edge by a diagonal 20 plate having diagonal marginal lines 2 2, which join the opposite marginal lines or edges 3 4, forming acute angles 5 5, the margin 3 extending beyond the diagonal margins 2 2. The outside edges of the eyeglass-guard 25 are marked 6 6.

Having thus described my invention, what I claim as new, and desire to secure by Letters Patent, is—

The design for an eyeglass-guard, as herein 30 shown and described.

FERDINAND KREUTER.
